WIRE SUPPORTING CLIP

Eugene M. Morehouse, Tujunga, Calif., assignor
to Adel Precision Products Corp., a corporation
of California

Application February 9, 1943, Serial No. 475,304

6 Claims. (Cl. 248—68)

This invention relates to devices for embracing and supporting a group of electrical wires and the like in aircraft in a manner similar to that disclosed in my pending application for patent entitled "Supporting clip for wires," Serial No. 449,919, filed July 6, 1942.

Wire supporting clips as shown in my application above identified and as heretofore made, primarily include a metal strap adapted to embrace and support a group of wires and a means for clamping the strap on the wires and securing the strap to a support. In my application above noted, the metal strap is provided with a cushioned seat for the wires.

It is an object of the present invention to provide an adjustable wire supporting clip which does away with the metal wire embracing strap and the separate cushion member heretofore employed and makes it possible to quickly and easily apply the clip to hold a plurality of wires in a compact group and securely fasten them to a support, with a single non-metallic strap which serves the purpose of the separate metal strap and cushion members heretofore used.

Another object of my invention is to provide a wire supporting clip for aircraft wherein a novel form of clamp associated with a single strap of flexible, non-metallic and compressible and preferably somewhat elastic material, such as synthetic rubber, makes it possible to set up sub-assemblies of wires and clips or the application of the clips after the installation of the wires; in either case with greater ease and in less time than heretofore.

A further object is to provide a clip of the character described which may be readily opened to remove or replace the wires without removing the clip from the support or manipulating the fastening means for securing the clip to the support.

Another object is to provide a clip of the character described wherein the single, flexible, elastic and compressible non-metallic strap makes for a more compact grouping of the wires in small compass, a better conformity of the strap to the group of wires and affords a cushioned support therefor to prevent damage and wear due to the vibration of the wires and clip, the elasticity of the strap providing a tensioned gripping and supporting action for the wires.

A further object is to provide in a clip such as described a clamp member for releasably drawing the ends of the flexible strap together to tightly grip the strap around groups of wires of various sizes and where the groups have vari-

ous diameters, it being unnecessary to preform the strap to generally conform to the group of wires, as heretofore, or to make up clips of different sizes, inasmuch as the single strap hereof will readily conform to wire groups of various diameters and the clamp provides for ready adjustment of the strap accordingly.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a front elevation of a clip embodying my invention as installed with the clamp in closed or clamping position;

Fig. 2 is a fragmentary front elevation of the clip with the clamp in open or releasing position;

Fig. 3 is a vertical sectional view taken on the line 3—3 of Fig. 1;

Fig. 4 is a side elevation of the clip as installed as shown in Fig. 1;

Fig. 5 is a cross section taken on the line 5—5 of Fig. 4;

Fig. 6 is an enlarged fragmentary sectional view showing the clamp in open or releasing position;

Fig. 7 is an enlarged front elevation of the body portion of the clamp showing how the flexible strap is secured thereto.

Referring to the drawing more specifically, it is seen that a wire supporting clip embodying my invention generally includes a flexible strap 1 of non-metallic, compressible and somewhat elastic material such as rubber, synthetic rubber, fabric or a rubberized fabric, with which an especially constructed clamp 2 is associated so that the strap may be given the form of a loop for embracing a group of wires or conduits designated 3 or a single wire or conduit, to support them in small compass on a frame or structural member 4 of the aircraft. A bolt 5 and a nut 6 are employed to secure the clamp to the support 4 in such manner that the clamp may operate to tightly secure the strap 1 around the wire or release the strap for removal and replacement of wires, without necessitating removing the clamp from the support or the manipulation of the nut 5 and bolt in any manner.

In accordance with this invention the strap 1 is adjustably associated with the clamp 2 so that wire groups of different sizes (diameters) may be accommodated with my improved clip. This arrangement makes it possible to support a single

conduit or wire or groups of wires of varying diameters over a large range.

As here provided the clamp 2 comprises a rectangular plate-like body portion 7, a movable jaw member 8 and a jaw actuating lever 9. One end of the strap 1 is secured to the body portion 7 by means of tongues 10 bent to clamp and hold said end as shown in Figs. 3 and 7.

The bolt 6 passes through an opening 11 in the body portion 7 to secure it to the structural member 4, said body portion having marginal reinforcing flanges 12.

The jaw member 8 is plate-like and has notches 13 in opposite edges receiving ears 14 struck out from body portion 7 whereby the jaw is held in place and is subject to movement towards and away from the body portion to clamp and release the strap 1 as shown in Figs. 3, 5 and 6. The inner end of the jaw member is formed with a curved lip portion 15 to accommodate the strap as shown in Fig. 3 so that a sharp edge contact of strap and jaw is eliminated. This lip portion also forces the strap into closer conformation with the wire group, as a loop portion.

The lever 9 is pivoted on a pin 16 mounted in and between the ears 14, said lever having marginal flanges 17 through which the pin extends as shown in Fig. 5. The inner end of the lever 9 is adapted to bear against the jaw member 8 and has a cam-like protuberance 18 extending outwardly, therefrom so as to bear against one side of the jaw member 8, when the lever is in clamping position as shown in Figs. 3 and 4. As the lever is then past center it will remain in clamping position thereby locking the clamp in clamping position with the opposite side of said jaw member pressed against the strap until the lever is forcibly moved into releasing position shown in Fig. 6.

To install the clip hereof the strap 1 is wrapped around the desired group of wires and after the free end portion of the strap is passed through the clamp to lie between the jaw member 8 and body portion 7, the strap is pulled tight and while tight is clamped in place. When the clamp is open, the lever 9 extends outwardly at right angles to the body portion as shown in Fig. 6. When the lever is raised or lifted the inner end thereof and the protuberance 18 thereon engage and force the jaw member 8 into clamping position, the tongues 10 then acting as jaws as shown in Fig. 3, whereby the end portions of the strap are tightly clamped together and so held with the strap tightly embracing the wires under tension. The lip portion 15 of the jaw member is disposed below the inner end of the lever 9 as shown in Figs. 3 and 4 and forces the strap into a closed tensioned loop surrounding and confining said wires to small compass in a cushioned seat by reason of the elasticity and compressibility of the strap. Moreover, this lip presses the loop portion of the strap downwardly and inwardly so as to hold the group of wires firmly against the support 4 to prevent a bouncing action.

In a sub-assembly operation the clip is applied before being affixed to the support 4. Otherwise the clip is first affixed to the support 4 following which the strap is wrapped around the wires and then clamped as hereinbefore described.

It is important to note that the long flexible strap 1 hereof may be used for a single wire or conduit or for groups of wires or conduits of varying numbers and sizes and with the groups of different diameters over a wide range. Any

extra length of the strap provided after it is clamped around a conduit or a group thereof may be cut off if desired.

In case of removal or replacement of the wires 5 the clamp may be easily opened without removal thereof from the support 4 and as readily re-clamped.

It is now seen that I have provided a simply constructed, light weight and inexpensive wire 10 clip by reason of the use of a flexible strap of non-metallic compressible material adapted to be wrapped around a wire or conduit or group thereof to form a supporting and cushioning loop portion therefor with the ends of the strap extending outwardly from the loop portion and subject to being clamped together to constrict the loop and facilitate the suspension thereof on a support.

While I have shown and described a specific 20 embodiment of my invention I do not limit myself to the exact details of construction set forth, and the invention embraces such changes, modifications and equivalents of the parts and their formation and arrangement as come within the 25 purview of the appended claims.

I claim:

1. In a supporting clip for wires or conduits, a 30 flexible strap of non-metallic compressible material adapted to be wrapped around a wire or conduit or a group thereof to form a supporting and cushioning loop therefor with the end portions of the strap extending outwardly from the loop and subject to being clamped together for constricting the loop portion and fastening it 35 on a support, a clamp body portion adapted to be attached to a support, means for fixing an end portion of the strap to said body portion, means including a lever pivoted to said body portion for releasably clamping and holding the other end portion of the strap on said body portion to provide and maintain a tensioned loop portion tightly embracing the wire, conduit or group thereof, and means independent of the clamping means for attaching the body portion to a support.

2. In a supporting clip for wires or conduits, a 40 flexible strap of non-metallic compressible material adapted to be wrapped around a wire or conduit or a group thereof to form a supporting and cushioning loop therefor with the end portions of the strap extending outwardly from the loop and subject to being clamped together for constructing the loop portion and fastening it on a support, a clamp body portion adapted to be attached to a support, means for fixing an end portion of the strap to said body portion, means including a lever pivoted to said body portion for releasably clamping and holding the other end portion of the strap on said body portion to provide and maintain a tensioned loop portion tightly embracing the wire, conduit or group thereof, and means independent of the clamping means for attaching the body portion to a support, said clamping means also engaging said loop portion and exerting a force to hold said loop portion against said support to prevent bouncing thereof relative to the support.

3. In a supporting clip for wires or conduits, a 50 flexible strap of non-metallic compressible material adapted to be wrapped around a wire or conduit or a group thereof to form a supporting and cushioning loop therefor with the end portions of the strap extending outwardly from the loop and subject to being clamped together for constricting the loop portion and fastening it on a support, means for attaching the clip to a support,

and means associated with the end portions of the strap for holding said ends clamped together to form a tensioned supporting loop embracing and supporting said wire, conduit or group thereof, including a jaw mounted upon the clip and having opposite side portions one of which contacts with said strap, and a lever mounted upon the clip to act upon the opposite side of said jaw for moving said jaw into clamping position, said jaw exerting pressure against said loop portion to hold the loop portion against said support.

4. In a supporting clip for wires or conduits, a flexible strap of non-metallic compressible material adapted to be wrapped around a wire or conduit or a group thereof to form a supporting and cushioning loop therefor with the end portions of the strap extending outwardly from the loop and subject to being clamped together for constricting the loop portion and fastening it on a support, a clamp body member, bendable tongues on said body member for fixing an end portion of the strap to said body portion, ears on said body portion, a movable jaw supported by and between said ears for movement toward and away from said body portion to clamp and release the other end portion of the strap, and a jaw actuating lever pivoted on said ears and engaging said movable jaw.

5. In a supporting clip for wires or conduits, a flexible strap of non-metallic compressible material adapted to be wrapped around a wire or conduit or a group thereof to form a supporting and

cushioning loop therefor with the end portions of the strap extending outwardly from the loop and subject to being clamped together for constricting the loop portion and fastening it on a support,

5 a clamp body member connected to an end portion of the strap and adapted to be secured to a support, a jaw on the body member movable to clamp the other end portion of the strap on said body member, a jaw-actuating lever on said body member having an end engaging said jaw, and a protuberance on one face of the lever adjacent said end thereof for engaging and holding said jaw in clamping position when the lever is in a predetermined position.

15 6. In a supporting clip for wires or conduits, a flexible strap of non-metallic compressible material adapted to be wrapped around a wire or conduit or a group thereof to form a supporting and cushioning loop therefor with the end portions of 20 the strap extending outwardly from the loop and subject to being clamped together for constricting the loop portion and fastening it on a support, a clamp body member, means carried by said body member for fixing an end portion of 25 the strap thereto, ears on said body portions, a movable jaw supported by and between said ears for movement toward and away from said body portion to clamp and release the other end portion of the strap, and a jaw actuating lever pivoted on said ears and engaging said movable jaw.
